UNITED STATES PATENT OFFICE.

WILLIAM DEMUTH, OF NEW YORK, N. Y.

DESIGN FOR A MOUTHPIECE FOR PIPES.

SPECIFICATION forming part of Design No. 26,104, dated September 29, 1896.

Application filed August 13, 1896. Serial No. 602,675. Term of patent 7 years.

To all whom it may concern:

Be it known that I, WILLIAM DEMUTH, a citizen of the United States, residing at New York, in the county and State of New York, have invented and produced a new and original Design for Mouthpieces of Tobacco-Pipes, of which the following is a specification.

My design is illustrated in the accompanying drawings, in which—

10 Figure 1 shows a face view. Fig. 2 shows a side view, and Fig. 3 shows an inverted plan view.

In the drawings the letter A designates the body of my mouthpiece, which is provided 15 with a nipple B, and from this nipple extend

two cylindrical legs C C. The nipple B is provided with a spiral groove or screw-thread, and this screw-nipple and the cylindrical legs C C form the leading feature of my design.

What I claim as new, and desire to secure 20 by Letters Patent, is—

The design for the mouthpiece of a tobacco-pipe as shown and described.

In testimony whereof I have hereunto set my hand in the presence of two subscribing 25 witnesses.

WILLIAM DEMUTH.
